UNITED STATES PATENT OFFICE.

JOHN B. ARCHER, OF WASHINGTON, DISTRICT OF COLUMBIA.

BOILER-FURNACE.

SPECIFICATION forming part of Letters Patent No. 341,623, dated May 11, 1886

Application filed March 18, 1885. Renewed November 19, 1885. Serial No. 183,369. (No model.)

To all whom it may concern:

Be it known that I, JOHN B. ARCHER, a citizen of the United States, residing at Washington, in the District of Columbia, have invented certain new and useful Improvements in Boiler-Furnaces; and I do hereby declare the following to be a full, clear, and exact description of the invention, such as will enable others skilled in the art to which it appertains to make and use the same.

My invention relates to that class of boiler-furnaces in which the fuel employed is gas or hydrocarbon vapor; and the nature thereof consists in certain novel constructions of parts hereinafter described and shown.

In the accompanying drawings, in which corresponding parts are designated by similar letters, Figure 1 is a longitudinal elevation, partially in section, of a boiler-furnace having my improvement applied thereto. Fig. 2 is a transverse vertical section on the lines $x x$ of Fig. 1. Fig. 3 illustrates in detail a tile constructed of fire-brick or other refractory material, which is placed in the fire-box of the furnace above the grate. Figs. 4 and 5 illustrate the gas-burner.

The cylindrical flue-boiler A has upon its under side one or more curved tiles, B, of fire-brick or other refractory material, which are provided with slots or receptacles for the upper ends of the posts or pillars C. These posts or pillars rest in holes formed in the flat tiles D, and are constructed of some highly refractory material which will resist the action of the flame and absorb and store up the heat generated by combustion. The gas or vapor enters the fire-box of the furnace immediately above the grate E by the pipe F, and the air to support combustion by the pipe H, and both of these pipes are provided with valves or stop-cocks to regulate or entirely shut off the flow of the gas or air through them. The grate E is arranged immediately below the point at which the gas or vapor enters the fire-box, and upon it are placed blocks or bricks constructed of fire brick, which are intended to absorb a portion of the heat generated by the combustion of the gas. Above the point at which the gas enters the fire-box is placed the U-shaped tile of fire-brick I, which is provided with holes upon its under side through which

a portion of the air from the hot-air chamber K flows downward upon the gas. As the specific gravity of the air is at equal temperature superior to that of the gas, the effect of this construction is to cause the former to sink through the latter and thus create an intimate intermixture of these fluids and a very perfect combustion. A projecting shelf or arch, L, of fire-brick, is arranged immediately above the U-shaped tile I, and with it forms a sinuous passage, through which the flame passes to the flue M beneath the boiler. Branch pipes o and o', provided with stop-cocks or valves for regulating the gas, lead from the main gas-induction pipes F to the burner N and N', which are supplied with the requisite amount of air to support the combustion of the gas from the air heating chamber P, formed in the furnace brick-work. The burner N is in this instance placed in front of the posts or pillars and the burner N' in the rear thereof, and the jets R are arranged in an inclined direction.

The construction of the burner is best shown in Fig. 4, in which O designates the gas-pipe, having a series of jets, R and T, the air-pipe provided with a number of cylindrical projections, U, which surround and inclose the gas-jets in such a manner as to form annular passage for the air. The air entering through the pipe H passes upward into the hot-air chamber K, which is formed by the partition-plate V, against which the products of combustion impinge on their way to the smoke-stack, and thence downward through another hot-air chamber in front of the fire-box to the point at which the gas enters through an opening, Y, provided with a damper. By means of these dampers the amount of air which enters above and below the grate E may be accurately adjusted and regulated. The air passing downward through the perforations in the tile I and upward through the grate E and refractory material placed thereon meets the gas or vapor entering through the gas induction-pipe F and promotes its combustion. The flame thus generated sweeps in a zigzag direction through the sinuous flue formed by the tile I and shelf or projection L into the horizontal flue M beneath the boiler, and the products of combustion, traversing the whole

length of the latter, pass through the tubular return-flues in the boilers to the smoke-stack, impinging on their way upon the partition-plate V, and thus imparting heat to the air-heating chamber K. The air entering the heating-chamber T passes into the air-tubes Z, which are provided with dampers, and from thence through the annular passages surrounding the branch gas-pipes R, where it comes into contact with the entering gas and supports its combustion. The flame thus generated re-enforces the heat of the flame generated in the fire-box, and passes in the manner hereinbefore described through the return-flues in the boiler to the smoke-stack.

In another application, No. 158,455, the combination of the tiles B and D, the posts C, and also the combination of the tiles, the posts, and the burner, is claimed. I therefore make no claim to these features in the present application.

Having thus described my invention, I claim and desire to secure by Letters Patent—

1. The combination of the burners N N', the tiles B and D, the posts, pillars, or blocks C,

and the boiler, as and for the purpose described.

2. The combination of the burners N N', the tiles B and D, the posts C, the air-heating chamber, and the boiler, as and for the purpose described. 30

3. The combination of the perforated tile I, which admits the air above the gas, the gas-induction pipe F, and the grate upon which is placed refractory material, as and for the purpose described. 35

4. The combination of the tile I, the gas-induction pipe, and the shelf or projection L, as and for the purpose described.

5. The combination of the air and gas-induction pipes and the boiler having an air-heating chamber, H, as and for the purpose described. 40

In testimony whereof I affix my signature in presence of two witnesses.

JOHN B. ARCHER.
